(57) **CLAIM**

We claim the ornamental design for a tattoo and permanent makeup device, as shown and described.

DESCRIPTION

FIG. 1 is a perspective view of a tattoo and permanent makeup device showing our new design;

FIG. 2 is a front elevation view thereof; and,

FIG. 3 is a left side elevation view thereof.

The right side elevation view is a mirror image of the left side elevation view shown in FIG. 3.

The broken lines in FIGS. 1-3 showing portions of a tattoo and permanent makeup device are included for the purpose of illustrating environmental structure and form no part of the claimed design.
